UNITED STATES PATENT OFFICE.

WILLIAM J. KEEP AND CHARLES WIPFLER, OF DETROIT, MICHIGAN.

DESIGN FOR A HEATING-STOVE.

SPECIFICATION forming part of Design No. 16,792, dated July 13, 1886.

Application filed April 24, 1886. Serial No. 900,072. Term of patent 7 years.

To all whom it may concern:

Be it known that we, WILLIAM J. KEEP and CHARLES WIPFLER, of Detroit, in the county of Wayne and State of Michigan, have invented new and useful Improvements in Stove Designs; and we do hereby declare that the following is a full, clear, and exact description thereof, reference being had to the accompanying drawing, which forms a part of this specification.

This invention relates to a certain new and original design for stoves, of which the following is a specification, reference being had to the accompanying drawing, forming part thereof.

The photograph is a perspective view of our newly-designed stove.

A is the ash-pit section of the stove. Its sides in rising from the bottom assume an outward incline upon a graceful curve, and, after forming a defined division-line at the upper edge, merge into a rounding top, which forms the base of the fire-pot.

Upon the sides and top the ash-pit section is provided with suitable ornamentation, and upon the rounding corners, under which the legs B are secured, this ornamentation simulates the presence of legs, so as to make the corners appear as forming the upper portions of the legs.

On top of the ash-pit section, at the two front corners, we construct draft-openings, which we provide with the medallion-shaped covers C. The fire-pot section E rises with a graceful outline above the ash-pit section, and upon the outwardly-bulging central portion thereof it supports the usual foot-rail, G. Its characteristic ornamentation is a corona of flames, H, around its upper portion. A pleasing break in the outline is produced by providing it with the enlargement I, which projects between the two front corners in the general form of a hood.

K is the combustion-chamber of the stove. Its general outline is cylindrical, and its exposed portions are subdivided into large panels highly ornamented. A conspicuous and pleasing ornament is produced by medallion-shaped covers L, placed over openings in some or all of the panels.

M is a dome-shaped top, the upper portion

forming a cover, as usual, and supporting an urn, statue, or other design as an ornamental finish.

N is a large circulating smoke-flue at the rear side of the stove. It forms a prominent and striking feature of the stove, owing to its size and peculiar shape and form. In plan it occupies a segmental space in the rear of the stove. Its base rests or apparently rests upon that portion of the ash-pit chamber in rear of the fire-pot section, and, extending upwardly and outwardly in a graceful outline and fully detached from the body of the stove, assumes in cross-section a segmental annular form with rounding corners, until with a graceful turn it joins onto the upper part of the stove. The exposed sides of the circulating smoke-flue are also highly ornamented in keeping with the rest of the ornamentation.

It will be seen that the leading motive of the ornamentation of the stove is a decorative application of the form of the flame more or less merged and combined with the scroll, the fire-pot section showing the flame as the single and central motive, and all minor surfaces are decorated in keeping with the rest of the ornamentation.

The leading features of this design consist of the representation of a flame of a spreading form and terminating in a scroll.

What we claim as our invention is—

1. In a design for a stove, an ash-pit section ornamented with a spread-flame ornament, and having its corners formed to simulate portions of the legs, substantially as shown.

2. In a design for a stove, the draft-doors upon the ash-pit chamber ornamented with a spread-flame ornamentation, as shown.

3. In a design for a stove, a fire-pot section ornamented with a flame-shaped corona, substantially as shown and described.

4. In a design for a stove, a fire-pot section with an outwardly-bulging central portion, having the hood-shaped projection I in front, and ornamented with a spread-flame ornamentation, as shown and described.

5. In a design for a stove, the fire-pot section E, ash-pit section A, and the rounding top of the base of the stove ornamented with a spread-flame ornament, all as shown and described.

6. In a design for a stove, the medallion-shaped covers L, forming ornamental center pieces, of the panel ornamentation of the combustion-chamber, and surrounded by a spread-flame ornament, substantially as shown and described.
7. In a design for a stove, a circulating smoke-flue, N, of segmental annular cross-section, partly detached from the stove, and extending between the ash-pit section and the top of the stove in the rear thereof, and having a spread-flame ornament, substantially as shown and described.
8. In a design for a stove, the combustion-chamber provided with a spread-flame ornament combined with the scroll, as shown and described.
9. In a design for a stove, the combustion-chamber ornamented with a spread-flame ornament combined with the scroll, substantially as shown and described.
10. In a design for a stove, the configuration and ornamentation of the ash-pit section, fire-pot section, and combustion-chamber, all having a spread-flame ornamentation, substantially as shown and described.
11. In a design for a stove, the configuration and ornamentation of the ash-pit section, fire-pot section, combustion-chamber, top, and circulating-flue N, all having a spread-flame ornamentation, substantially as shown and described.

WILLIAM J. KEEP.
CHARLES WIPFLER.
